TOY PLAY TABLE OR SIMILAR ARTICLE

Don A. Taylor, Wadsworth, Ohio

Application April 21, 1955, Serial No. 35,618

Term of patent 14 years

(Cl. D34—15)

Fig. 1 is a perspective view of a toy play table or similar article, showing my new design;

Fig. 2 is an enlarged top plan view thereof;

Fig. 3 is an enlarged side elevational view thereof; and

Fig. 4 is an enlarged front elevational view thereof.

I claim:

The ornamental design for a toy play table or similar article, as shown.
